UNITED STATES PATENT OFFICE.

ADOLF STEFFEN, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

DESIGN FOR AN ART METAL SHADE FRAME.

61,178.

Specification for Design.

Patented July 4, 1922.

Application filed May 18, 1921. Serial No. 470,614. Term of patent 7 years.

To all whom it may concern:

Be it known that I, ADOLF STEFFEN, a citizen of the United States, residing at Pittsburgh, in the county of Allegheny and State of Pennsylvania, have invented a new, original, and ornamental Design for an Art Metal Shade Frame, of which the following is a specification, reference being had to the accompanying drawing, forming part thereof.

Fig. 1 of the drawing is a top plan view showing my new design; and Fig. 2 is a side elevational view thereof.

I claim:

The ornamental design for an art metal shade frame, as shown.

ADOLF STEFFEN.

Witnesses:

LOIS WINEMAN,
JOHN B. EBERLEIN.
